FIG-3-

INVENTOR

David A. Leinsetter,
By *Cornelius & Cramford*,
Atty.

UNITED STATES PATENT OFFICE.

DAVID A. LEINSETTER, OF LEIPSIC, OHIO.

SANITARY WASHSTAND.

1,426,488.

Specification of Letters Patent. Patented Aug. 22, 1922.

Application filed December 22, 1921. Serial No. 524,082.

To all whom it may concern:

Be it known that I, DAVID A. LEINSETTER, a citizen of the United States, and a resident of Leipsic, in the county of Putnam and State of Ohio, have made an Invention 5 Appertaining to a Sanitary Washstand; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates to washstands, and particularly to one for use in rural districts.

The object of my invention is the provision of a simple, efficient and inexpensive 20 wash stand of the character described, which is sanitary in its nature, is capable of being easily cleaned, and which employs an elevated water supply tank in position to supply running water to the trough member 25 and to have its water discharge from one or more faucets down onto an inclined surface of the trough member to prevent splashing.

The invention is fully described in the 30 following specification, and while, in its broader aspect, it is capable of embodiment in numerous forms, a preferred embodiment thereof is illustrated in the accompanying drawings, in which,

35 Figure 1 is an end elevation of the washstand. Fig. 2 is a front elevation thereof, and Fig. 3 is a fragmentary vertical section of the washstand on the line 3—3 in Fig. 2.

Referring to the drawings, 1 designates 40 the trough or sink member of the washstand, which member is supported by a suitable framework 2 in position for the bottom of the trough to be slightly inclined from one end to the other thereof to facilitate water flowing by gravity to one end 45 thereof from which it drains through a drainage pipe 3 into a bucket 4 or other receptacle provided for such purpose. The trough 1 is provided with front and end 50 walls 5 and 6, respectively, and has its bottom 7 downwardly inclined at a slight angle rearwardly from the front wall to the lower edge of the upwardly and rearwardly inclined back wall 8 of the trough. The back 55 wall 8 continues its incline a distance above and to the rear of the trough 1 and is of

such an angle that a stream of water falling thereon from above will be deflected downwardly into the trough without splashing. The back wall 8 terminates at its upper end 60 in an upright back portion 9, which is secured to the front side of and supported by the rear frame uprights 10, which extend a distance above the trough. The trough bottom 7 and back 8 are supported by the 65 cross-members 11 of the frame, which are preferably of angle-iron, and extend from the front to the rear edge of the bottom 7 and thence upward and rearward under the back wall 8 in supporting contact therewith, being secured at their rear ends to the uprights 10. The front ends of the cross-pieces 11 preferably have flanges 12 turned upward therefrom in holding contact with the front side of the trough. 70

Bracket-arms 13 extend forward from the upper ends of the uprights 10 through the back upright 9 and support a tank 14 for containing a supply of water. The tank is intended to loosely rest on the supporting 80 arms so that it may be easily removed therefrom for the purpose of cleaning or dumping and is held against the back 9 by lips 15 extending upward from the forward ends of the bracket-arms. The tank is provided 85 at its bottom with one or more downwardly directed discharge faucets 16, the number depending on the length of the trough, such faucets being disposed near the front edge of the tank and in position for the streams 90 of water discharging therefrom to strike the inclined trough back 8 preferably a short distance above its lower edge, as shown in Fig. 3, thereby preventing splashing of the water falling thereon. 95

It is evident that my washstand is strong, durable and inexpensive in its construction, capable of being easily kept clean, and is of a nature particularly adapting it for use in rural schools, farm houses, and the like. 100 The tank 14 is capable of being quickly drained or dumped to prevent freezing and the trough is so constructed that the water will quickly drain therefrom, thereby rendering it sanitary and preventing freezing. 105

I wish it understood that my invention is not limited to any specific construction, arrangement, or form of the parts, as it is capable of numerous modifications and changes without departing from the spirit 110 of the claims.

Having thus described my invention, what

I claim as new, and desire to secure by Letters Patent, is,—

1. A washstand of the class described, comprising a frame, a longitudinally inclined trough supported by the frame and having a drainage passage at the lower end of its incline, the bottom of the trough being slightly inclined downward and rearward from its front edge and the back of the trough being inclined upward and rearward from the rear edge of the trough bottom and a distance above and to the rear of the trough and then extending upright, the frame having rear upright members supporting the back, bracket-arms projecting from such members above the inclined back, a tank mounted on the bracket-arms and having provision for discharging one or more streams of water therefrom down onto the inclined back of the trough near its lower edge.
2. A washstand of the class described, comprising a trough, which is longitudinally inclined and provided at the lower end of its incline with a drainage passage, the

trough having a front member, end members, a bottom member inclining downward and rearward from the front member, and a back member inclining upward and rearward from the rear edge of the bottom member and extending a distance above and to the rear of the trough and then upward a distance in upright position, a frame supporting the trough and having cross-pieces extending under the trough bottom and thence upward under the inclined back in supporting contact with both and also having upright members extending up at the rear of the upright portion of the back member in supporting engagement therewith and having forwardly extending bracket arms a distance above the trough back, and a tank removably supported by the bracket-arms and having provision for the discharge of one or more streams of water therefrom down onto the inclined back member of the trough near its lower edge.

In testimony whereof I have hereunto signed my name to this specification.

DAVID A. LEINSETTER.
